[57] CLAIM

The ornamental design of an interlocking jewelry ring, as shown and described.

DESCRIPTION

FIG. 1 is a perspective view of a first embodiment thereof;

FIG. 2 is a top plan view of a first embodiment thereof;

FIG. 3 is a side elevational view of a first embodiment thereof;

FIG. 4 is a front elevational view of a first embodiment thereof;

FIG. 5 is a rear elevational view of a first embodiment thereof;

FIG. 6 is a bottom plan view of a first embodiment thereof;

FIG. 7 is a perspective view of a second embodiment thereof;

FIG. 8 is a top plan view of a second embodiment thereof;

FIG. 9 is a side elevational view of a second embodiment thereof;

FIG. 10 is a front elevational view of a second embodiment thereof;

FIG. 11 is a rear elevational view of a second embodiment thereof;

FIG. 12 is a bottom plan view of a second embodiment thereof;

FIG. 13 is a perspective view of a third embodiment thereof;

FIG. 14 is a top plan view of a third embodiment thereof;

FIG. 15 is a side elevational view of a third embodiment thereof;

FIG. 16 is a front elevational view of a third embodiment thereof;

FIG. 17 is a rear elevational view of a third embodiment thereof; and,

FIG. 18 is a bottom plan view of a third embodiment thereof.
